DESIGN FOR AN ARTIFICIAL TOOTH SHADE GUIDE CASE

Albert Francis Lays, Pelham Manor, N. Y., assignor to The Dentists' Supply Company of New York, New York, N. Y., a corporation of New York

Application March 31, 1939, Serial No. 83,945

Term of patent 3½ years

To all whom it may concern:

Be it known that I, Albert Francis Lays, a citizen of the United States and a resident of Pelham Manor, in the county of Westchester and State of New York, have invented a new, original, and ornamental Design for an Artificial Tooth Shade Guide Case, of which the following is a specification, reference being had to the accompanying drawing, forming a part thereof.

Figure 1 is a perspective view of an artificial tooth shade guide case in closed position, showing my new design.

Figure 2 is a top plan view of the same in opened position, and

Figure 3 is a fragmentary vertical sectional view taken on the line 3—3 of Figure 2.

The dominant features of my design reside in the portions shown in full lines.

I claim:

The ornamental design for an artificial tooth shade guide case, as shown and described.

ALBERT FRANCIS LAYS.
